UNITED STATES PATENT OFFICE

LOU OBSTFELD, OF BROOKLYN, AND WILLIAM DRYPOLCHER, OF VALLEY STREAM, NEW YORK, ASSIGNEES, BY MESNE ASSIGNMENTS, TO SAID LOU OBSTFELD AND ABRAHAM I. OBSTFELD, OF NEW YORK, N. Y.

STAPLING MACHINE

Application filed December 6, 1929. Serial No. 412,251.

This invention relates to improvements in stapling machines of the type embodying a hand operated hammer for driving wire staples or fasteners, which are automatically fed from a magazine one at a time into the path of the hammer.

The invention has for its object to provide a stapling machine of this character which is designed to meet the most rigid economical manufacturing conditions without detracting from its efficiency or appearance.

A further object of our invention is to provide a stapling machine having the magazine designed to be loaded at the front end which is closed by a spring gate or door designed to be opened in two steps, the first step being only a partial opening to prevent the staples, held under spring pressure in the magazine, from projecting outwardly and resulting in possible injury to the operator, while the second step requires the manual operation of the operator to release the gate, from its partially open position, and swing it to full open position.

Another object of the invention is to provide a locking spring releasably carried in the hammer guide to limit the upward movement of the hammer.

A still further object of our invention is to provide a staple slide having a latch to engage a portion of the magazine case to hold the slide against the full tension of its spring while the magazine is being reloaded.

And a still further object of our invention is to provide a staple retractor and means for assembling the latter in the front end of the magazine case after the entire machine has otherwise been completely assembled.

We accomplish these objects by means of the arrangement and combination of parts hereinafter described in the specification, set forth in the claims, and illustratively exemplified in the accompanying drawings, in which Figure 1 is a substantially longitudinal sectional view of my improved stapling machine showing the hammer and magazine case in normal raised position; Figure 2 is a front elevational view of the plunger housing; Figure 3 is a top plan view of the rear portion of the magazine showing the staple

slide and latch; Figure 4 is a substantially transverse sectional view of the magazine taken on line 4—4 of Figure 1; Figure 5 is a substantially longitudinal sectional view of the staple retractor and outer end of the 55 magazine case showing the manner in which the retractor is assembled; Figure 6 is a substantially longitudinal sectional view of the magazine taken on line 6—6 of Figure 1; Figure 7 is a longitudinal sectional view of the 60 lower end of the plunger housing, hammer and clincher device showing the plunger in its depressed position; Figure 8 is a transverse sectional view of the clincher device taken on line 8—8 of Figure 1; Figure 9 is a transverse sectional view taken on line 8—8 65 of Figure 7; Figure 10 is a bottom plan view of the knob; and Figure 11 is a substantially cross sectional view of the knob taken on lines 11—11 of Figure 10; Figure 12 is a top 70 plan view of the plunger housing; Figure 13 is a front elevational view of the plunger housing and gate; Figure 14 is a front elevational view of the plunger and blade; and Figure 15 is a transverse sectional view of the 75 same taken on line 15—15 of Figure 14.

Referring to the drawings, our improved stapling machine comprises an elongated base plate 10 having a pair of spaced upright ears 11 bent from the mid portion of 80 the base adjacent the rear end thereof. Adjacent the front end of the plate 10 the material is struck up to form a cylindrical clincher housing case 12 in which the 85 clincher mechanism hereinafter described is encased as illustrated in Figures 1, 7, 8 and 9.

Pivottally mounted between the upright ears 11 on a transverse pin 13 is a magazine case 14, which comprises a length of channel bar 90 having its sides bent inwardly and parallel to the bottom with the intervening space to accommodate a staple slide 15. The extreme rearward end of the case 14 is bent downwardly to form a stop lip 16 and adjacent the latter in the bottom wall is a slot 17 projecting transversely thereof, to accommodate one end of a flat spring 18, which at the same end beyond the slot 17 95 follows the bottom wall to its end and then 100

turns upright to form a stop or seat 19 for one end of the staple spring 20, and which in a forwardly direction beyond the slot 17 projects outside and against the bottom of the case 14 to a point short of the pin 13, where it bends downwardly under tension to engage in a slot in the under side of the pin and bear at its forward end upon the surface of the base plate 10. The spring 18 rearwardly of the pin 13 tends to exert a downward pull on the rear of the magazine case 14 and as a consequence yieldably supports its forward end at an elevation substantially above that of the base plate.

15 Permanently mounted within the magazine case 14 is a core 21 of substantially the same shape as the latter except that its dimensions are somewhat smaller, so that when the bottom walls of the case 14 and core 21 are welded together in superimposed position, as illustrated in Figures 1 and 4, there will be a space provided along the top and sides to accommodate the staple slide 15 and staples A. The staple spring 20 is a 25 spiral member with flat sides to fit inside the walls of the core 21 and at its forward end abuts a downwardly turned projection 22 of a staple latch 23 which is carried by the slide 15 and held in sliding contact there- 30 with by an end groove formed by a turned over portion 24 of the slide, the latch itself being turned back on itself in the groove and provided with a cut outside portion to form a tooth 25. The turned end of the 35 latch terminates in an upturned finger piece 26. The projection 22 of the latch 23 enters the interior of the core 21 through an opening 27 which has its forward wall disposed at an angle to form a tapered open- 40 ing. This opening 27 allows the latch to be swung in the direction of its tooth 25 to engage a notch 28 cut in the edge of the top wall of the magazine case 14. To remove the tension of the spring 20 on the 45 staples A the slide 15 is drawn as far back as possible or until the latch 23 swings into a position to engage the tooth 25 in the notch 28.

46 The forward free end of the magazine case 14 is provided with an upright plunger housing 30, which comprises an upper tubular portion, square in transverse section and having its side walls 31 projecting rearwardly beyond the side walls 50 and downwardly to embrace the sides of the magazine casing 14, as illustratively exemplified in Figures 1 and 2. The lower end of the rear wall of the housing 30 is bent inwardly to form a seat 32, the center of the latter being struck up to provide a boss 33 for the purpose of centering the lower end of a coiled spring 34. The housing 30 is welded to the magazine case 14 at several 55 points of contact so that the two parts after

assembly become virtually a single integral unit.

The housing 30 is guideway for a plunger 35 which is a length of square or rectangular tubing slidably mounted longitudinally in 70 housing 30, and which is provided at its upper end with a knob 36, the latter being a stamping having a dome-shaped top and a square or rectangular socket 37 depending therefrom by means of two straps 38, as 75 shown in Figures 10 and 11. The plunger 35 is yieldably supported in its uppermost position by the upper end of the coiled spring 34 which seats against the inner surface of the knob 36. The plunger 35 is removably mounted in the housing 30 and limited in its movements therein by a plunger stop spring 39, which has one end turned under to form a hook 40, while the portion adjacent the opposite end is offset to form a stop 41 and 80 curved tip 42. The hook 40 engages the lower portion of the back wall of the plunger housing 30 by being inserted under a strap 43 formed by a punched out section of the housing. The stop portion 41 of the spring 85 39 is yieldably held in position in a slot 44 in the rear wall of the housing and projects therethrough to enter an elongated slot 45 in the adjacent wall of the plunger 35, as 90 shown in Figure 1. It will be clear that longitudinal movement of the plunger 35 is limited to the length of its slot 45 where the ends of the latter abut the opposite sides of the stop 41 of the spring 39. Removal of the plunger 35 from the housing 30 is 95 facilitated by merely raising the stop portion 41 outwardly from the slot 45 which frees the plunger and allows it to be drawn upwardly out of the housing.

Referring now particularly to Figure 14, 100 it will be seen that the front wall of the plunger 35 is provided with two spaced circular shaped bosses 46, which are stamped outwardly from the lower half of the plunger wall. These offsets 46 are adapted to project into similarly shaped openings 47 punched out of a plate 48 forming the steel blade or die which after being formed and shaped is hardened and properly tempered. The openings 47 are provided in the upper 110 half of the blade 48 so that when placed on the offsets 46 the lower end portion of the blade projects downwardly below the plunger 35 and on a plane just forward of the front wall of the plunger. The lower end 115 of the blade is cut away slightly to points just short of the sides to form a pair of fingers 49 curved on their inside walls. The purpose of the fingers 49 is to embrace the opposite ends of the staple A during the driving operation of the plunger, as illustratively exemplified in Figures 8 and 9. The lower portion of the blade below the lowermost opening 47 is slightly thinner than its upper part so that there is a space between its 120

forward face and that of the adjacent surface of the front wall of the housing 30, see Figures 1 and 7. It is to be noted further that the lower end, including the fingers 49, is supported in normal position on an elevation level with the under surface of the bottom wall or seat 32, and that the latter is disposed in fixed position over the free end of the magazine case 14.

As previously stated, the magazine is loaded at its forward end and the staples A are disposed along the passage between the walls of the magazine case 14 and core 21 from the pusher 22 to the outer end. To facilitate loading the magazine a gate 50 is mounted at one side of the housing 30 as illustrated in Figures 1, 7 and 13, on a pin hinge 51 which is supported in upright position between one of two pair of ears 52 welded in position on the housing, the other pair of ears being mounted on the opposite side of the housing 30 and provided with a latch pin 53.

The magazine gate or door 50 is cut from a single piece of spring steel having a flat front portion cut away at its lower section to provide an opening 54. The front portion is turned rearwardly at right angles to overlie the sides of the plunger housing 30, see Figure 6, and from the mid portion of each end a narrow tab 55 projects, one tab being turned on itself to form an eye 56 turning on the hinge pin 51, while the other tab is bent outwardly and rearwardly at one inclination, then in a semi-circle towards the eye 56 to form the latch 57 and finally in a reverse curve to provide a finger tip 58. In the closed position, illustrated in Figure 6, the latch 57 is shown engaging the latch pin 53 to hold the magazine door 50. The door 50, if accidentally released by bringing the latch 57 over the latch pin 53, will have the entire force of the spring 34 behind the staples A tending to drive it to full open position with a result of possible injury being inflicted upon the operator from the projected staples A. We have overcome the possibility of such a mishap by means of a coiled spring 59, which at its ends is coiled about the hinge pin and bears against the side wall of the housing 30 in back of the ears and which at its mid portion is disposed about the ears and spans the space between the latter, the mid portion being under tension and held against the forward side of the ears and in the path of the hinged side of the door 50 when the latter swings to open position. It is the purpose of the spring 59 to overcome the inertia of the spring 34 to force the door to its full open position so as to allow the staples to escape. Therefore, the first step in swinging the door to open position is to release its latch 57 and then after being swung to a partially open position and against the mid portion of the spring 59, it is necessary to force the door against the spring 59 which

will yield and allow the full end of the magazine to be exposed for refilling purposes. It is assumed that an operator, having accidentally released the door 50 before making the staple latch 23 fast to the magazine case 14, and experiencing the shock of having the door 50 suddenly fly to partially open position as the latter engages the spring 59, will be reminded to draw the staple latch 23 back towards the rear of the magazine 14 and engage the tooth 25 in the notch 28 to hold the staple spring 20 retracted, before forcing the door to its full open position.

In order that the staples A may be properly delivered one at a time to a position directly in the path of the descending blade 48, we mount a staple retractor in the end of the core 21, as illustratively exemplified in Figures 1, 5, 6 and 7. The staple retractor comprises a pedestal 60 having an angular wall 61 forming the rear and bottom and upright side walls 62 which are curved at their free ends from the top of the angular wall to the end of the bottom portion thereof. Two lugs 63 are punched out of the bottom portion of the pedestal 60 to form at their lower sides straight surfaces adapted to rest upon the lower or closed surface of the core 21 which is turned up at its end to provide a lip 64 to receive the end of the bottom portion of the pedestal while the rear ends of the lugs 63 rest against lugs 65 struck up from the bottom wall of the core 21. The manner in which the pedestal 60 is placed in the core is illustrated clearly in Figure 5. The sides 62 carry a pin 66 therebetween upon which the ear portions 67 of a tongue 68 are pivotally mounted. The tongue 68 is a flat piece of metal which swings upwardly against the open top portion of the core 21 and which projects outwardly through the path of the blade 48 and is normally held in engagement with the top side of the opening 50, as illustrated in Figure 1. The tongue 68 is yieldably supported in this position by coiled spring 69 which coils about the pin 66 and engages at its opposite end respectively against the tongue 68 and bottom wall of the pedestal 60. It will be seen, according to Figure 7 that as the blade 48 is driven downwardly, the staple A in its path is projected between the gate and the end of the core 21 and against the tongue 68 which yields to the pressure and swings about the pin 66 until the cross or closed end of the staple is far enough on its way to pass the end of the tongue, as illustrated in Figure 7. The succeeding staple still in the ways is prevented from further movement by the upper portion of the blade, but as the latter lifts and returns to its initial position the tongue 68 follows the end of the blade in its upward movement, which finally reaches an elevation above that of the staples, whereupon the forward staple moves forward and into the

path left by the receding blade, but instead of dropping its closed end rests upon the end of the tongue 68 and against the inner face of the gate 50. A particularly important feature of this arrangement is the ease with which the parts may be removed and inserted again in the event of repairs being necessary.

The clincher mechanism is mounted in the housing 12, as illustrated particularly in Figures 1, 7, 8 and 9, and comprises a two piece cap shaped case 70 which is mounted in the housing 12 and provided with a lug 71 projecting from its side wall into a groove 72 in the adjacent wall of the housing. The case 70 is a stamped member and about midway of its height a flange 73 is arranged against which a heavy coiled spring 74 seats at one end while the other end of the spring bears against a disc 75 fitting tightly in the base plate 10 at its under side to close the opening formed by the metal upturned to form the housing 12. The top wall of the clincher case 70 is provided with a diametrically disposed slot 76 directly in line and beneath the blade 50 when the latter is depressed with the hinged casing 14. The slot 76 is formed by turning the metal downwardly on opposite sides of a slit cut in the cover. Pivottally mounted on pins 77 mounted in the side walls of the slot 76, adjacent opposite ends thereof, are clincher jaws 78, each thereof being a flat piece of material with an inwardly curved upper side 79 which ends in an upturned tip and straight end side 80. The ends 80 are arranged in very close proximity to each other when the staple A is being clinched, as illustrated in Figure 9. The under sides of the jaws 78 are rounded outwardly to form cam surfaces 81. Each jaw 78 has a projection 82 on its side to limit their upward movement about the pins 77, the projections 82 engaging the lower end of one of the side walls of the slot 76. Reciprocally mounted in the clincher casing 70 is a jaw supporting member 83 upon the upper surface of which the cam surfaces 81 rest. The skirt portion of the member 83 is slidably fitted against the cylindrical interior of the case 70. A coiled spring 84 yieldably supports the member 83 in which it is housed, the spring 84 being in contact with the disc 75 at one end and the member 83 at the other end.

55 The operation of the device is as follows: Assuming that the magazine is charged with staples A and it is desired to fasten a package of papers together, the latter is placed over the clincher case 70 and the blade 50 driven downwardly by depressing the knob at the upper end of the plunger 35, from the position of Figure 1 to that of Figure 7. Continued movement of the blade 50 causes the ends of the staple A to pierce the package and strike the inwardly curved upper

sides of the jaws, which while they spread under the pressure of the blade, the resistance offered by the spring supported member 83 is sufficient to turn the staple ends inwardly to the position shown in Figure 8. The final movement of the blade brings the staple to the position shown in Figure 9 where it is completely clinched and the support 83 resting directly on the disc 75. When the plunger is released it springs upwardly and allows the clincher case 70 to ride up under tension of the spring 74 until the flange 73 is stopped by the flange 85 at the upper end of the housing 12.

Having now described our invention and the manner in which the same operates, what we claim and desire to secure by Letters Patent is:

1. In a stapling machine, the combination of a staple-carrying arm for receiving and discharging the staples from the same end, a staple driver reciprocable on the arm, means for feeding the staples along the arm and into the path of the driver, and means disposed over the loading and delivery end of the arm to hold the staples in the driving position when closed and capable of only partial unresisted movement to open position when released.

2. In a stapling machine, the combination of a staple-carrying arm for receiving and discharging the staples from the same end, a staple driver reciprocable on the arm, means for feeding the staples along the arm and into the path of the driver, hinged means disposed over the receiving and discharging end of the arm, and resilient means engaged by the hinged means upon reaching partial open position for resisting movement of the hinged means to full open position.

3. In a stapling machine, the combination of a staple-carrying arm pivotally mounted and yieldably supported adjacent one end, a staple driver reciprocable on the free end of the arm, means for feeding the staples along the arm and into the path of the driver, a hinged door for the free end of the arm to hold the staple in the path of the driver against the pressure of the feeding means, and resilient stop means to be engaged by the door in its partially open position.

4. In a stapling machine, the combination of a staple carrying arm pivotally mounted and yieldably supported adjacent one end, a staple driver reciprocable on the free end of the arm, means for feeding the staples along the arm and into the path of the driver, a door hinged at one side of the free end of the arm and in closed position forming one wall of the path of the staples under the driver, and resilient means to arrest movement of the door to open position beyond a point directly in the path of the staples being projected along the arm.

5. In a stapling machine the combination

- of a staple carrying arm pivotally mounted and yieldably supported adjacent one end, a staple driver reciprocable on the free end of the arm, means for feeding the staples under pressure along the arm and into the path of the driver, a door hinged at one side of the driver and in closed position forming one wall of the path taken by the staples under the driver, and a spring comprising a coiled portion disposed co-axially of the swinging axis of the door, opposite ends of the spring being fixed and the mid portion forming a stirrup supported under tension of the coils in the path taken by the door swinging to open position, engagement of the door with the spring taking place when a portion of the free end of the door is still in the path of any staples being projected by the feed from the open end of the arm.
6. In a stapling machine, the combination of a staple carrying arm pivotally mounted and yieldably supported adjacent one end and adapted to be loaded and discharged from the free end, a staple driver reciprocable on the free end of the arm, means for feeding the staples along the arm under pressure and into the path of the driver, a door hinged at one side of the driver and comprising a U-shaped member, the cross portion of which closes over the open end of the arm to form the outside wall of the path taken by the staple under the driver, the free end of the door having a portion to yieldably hold the door in closed position and a projection beyond said portion to remain in the path of the staples when projected beyond the path of the driver, and a spring stop for the hinged end of the door to yieldably resist the door in its movement to open position beyond a point where said projection would be in the path of the staples being projected from the open end of the arm.
7. A stapling machine, as claimed in claim 5, in which the cross piece of said door is cut away at its under side to form a slot, and a staple retractor mounted in the free end of the arm and having a yieldable arm projecting across the path of the driver and supported against a wall of said slot to support a staple in the path of the driver.
8. In a stapling machine, the combination of a staple carrying arm comprising an outer and an inner casing spaced apart on top and at their sides to form a passage for the staples, the upper wall of both casings having longitudinal openings, a staple driver reciprocable on the end of the arm, means for feeding the staples along the arm and into the path of the driver, a hinged door for the driver end of the arm having an opening, the upper wall of which is below the space between the two upper walls of the casings, and a retractor for the staples comprising a pedestal detachably mounted in the arm back of the said door, a tongue pivotally mounted in the pedestal and having the tip and movable through the path of the driver and opening in said door, and a spring yieldably supporting the tongue against the upper end of said opening in the door to support a staple in the path of the driver, said tongue when depressed being inside the path of the staple and driver.
9. A stapling machine, as claimed in claim 8, in which the inner casing at its end adjacent the door is cut away and turned up to form a lip against which one end of the pedestal is engaged, said inner casing being further provided with lugs to receive the other end of the pedestal.
10. In a stapling machine, the combination of a staple carrying arm comprising an outer casing and an inner core spaced from each other on the top and two sides to form a magazine passage for the staples, said casing and core having longitudinal openings along their top walls, a staple driver reciprocable on one end of the arm, a hinged door for the driver end of the arm, and means for feeding the staples along the magazine passage and into the path of the driver, comprising a spring arranged in said core, a staple slide in said passage between the loose end of the spring and the staples, a pivotal support adjacent the spring end of the arm, and a spring for resiliently supporting the arm in raised position and projecting into the core to form a seat for the fixed end of the spring for projecting the slide, and means carried by the slide and adjustable to one side for latching the slide to the casing to hold the said spring under tension.
11. In a stapling machine, the combination of a staple carrying arm, a plunger housing on one end of the arm, a plunger reciprocable in said housing, comprising a tubular member rectangular in transverse section, a blade mounted on one end of the plunger, and a one piece knob for the other end comprising a dome shaped portion provided with radial T-shaped projections, the stems of which are bent under the dome portion and the cross pieces are bent to abut each other at their ends to form a rectangular shank disposed axially of the dome and adapted to embrace the end of the plunger opposite the blade.
12. In a stapling machine, a standard having a base with upturned ears at one end and a raised circular portion at the other, a staple carrying arm pivotally mounted at one end between said ears, a staple driver reciprocable on the other end of the arm, and means for clinching the staples driven by said driver, comprising a case spring supported in said circular portion of the base, a pair of oppositely disposed jaws pivotally mounted in the case and having their free ends projecting towards each other, the upper walls of the jaws being inwardly curved and terminating in a raised tip, and a second casing spring supported within the first casing and supporting the jaws from underneath, whereby

a staple being driven by downward movement of the driver will engage the curved walls of the jaws and turn the jaws downward which first turn the staple ends towards each other and then under pressure the outer casing recedes and lowers the pivotal ends of the jaws causing the free ends to rise to turn the staple ends upwardly.

13. A stapling machine, as claimed in claim 12, in which the circular portion of the base is provided with a shoulder at its lower open end, and a disc driven into the base against the shoulder to form a seat for the said casings in depressed position.

14. A stapling machine, as claimed in claim 12, in which the upper end of the circular portion is inwardly flanged and provided with a longitudinal guideway on its side, the outer casing being provided with a flange midway of its height and a lug projecting radially of the side wall to move in said guideway.

In testimony whereof they have affixed their signatures.
